[57] ABSTRACT

A sewing machine is disclosed in which the needle thread manipulating instrumentalities including a thread tensioning device, a check spring, and a thread take-up member may be threaded by the act of inserting into the machine a cassette including a supply of thread with provision for guiding and positioning the thread from the supply for introduction of the thread to the sewing machine thread manipulating instrumentalities when the cassette is inserted in the sewing machine.

CASSETTE THREADING ARRANGEMENT IN SEWING MACHINES

BACKGROUND OF THE INVENTION

It is difficult to thread a conventional sewing machine, not only because of the number of different thread guides through which the thread must be directed, but because the sequence of threading of the various guides must be observed meticulously if the sewing machine is to operate successfully.

Self-threading guides are known whereby an operator may introduce the thread laterally into the eyelets without releasing grasp of the thread but these self-threading guides do not obviate the problem raised by the requirement that each guide must be threaded successively and in precise sequence.

The U.S. Pat. No. 3,385,247, May 28, 1968 of R. E. Johnson et al. discloses an arrangement for facilitating the thread supply for a sewing machine needle by combining the thread supply and the stitch-forming instrumentality (needle) in one insertable package in the machine. This patented construction, however, can be used only with the most rudimentary stitch-forming arrangement and is not adapted for use with a sewing machine which utilizes conventional thread manipulating elements such as a thread tensioning device, check spring and thread take-up mechanism.

BRIEF SUMMARY OF THE INVENTION

It is an object of this invention to provide an easy threading arrangement for a thread-carrying sewing machine stitch-forming instrumentality, such as a needle, of the type which is adapted to cooperate with conventional types of thread manipulating elements. The object of this invention is attained by the provision of a thread cassette in which a supply of thread is stored and in which thread guides and nippers are provided for positioning the thread such that upon insertion of the cassette into the sewing machine, the sewing machine thread manipulating elements will automatically be threaded properly.

DESCRIPTION OF THE DRAWINGS

In the accompanying drawings of a preferred embodiment of this invention:

FIG. 1 is a perspective view of a sewing machine having a thread cassette of this invention inserted therein,

FIG. 2 is an enlarged perspective view of the cassette with the cassette lid opened showing the path of the thread in the cassette,

FIG. 3 is an enlarged elevational view of the cassette with the lid removed and including fragments of the sewing machine frame in vertical cross-section showing the cassette completely seated in the sewing machine and illustrating the thread introduced to the sewing machine thread manipulating elements.

FIG. 4 is a bottom plan view of the cassette completely seated in the sewing machine as shown in FIG. 3,

FIG. 5 is a perspective view of a fragment of the sewing machine frame including the space for accommodating the cassette, but with the cassette removed,

FIG. 6 is an enlarged perspective view of the sewing machine thread tension and check spring devices and including a fragment of the cassette which operates the retractable thread guide associated with the check spring,

FIG. 7 is an enlarged and elevational view of the sewing machine with portions broken away to illustrate the provisions for directing thread from the cassette to the sewing machine thread take-up arm,

FIG. 8 is a perspective view of the thread directing fin on the sewing machine for directing thread from the cassette to the thread take-up arm,

FIG. 9 is a disassembled perspective view of those parts on that portion of the cassette which presents a span of thread to the thread directing fin of FIG. 8,

FIG. 10 is a cross-sectional view taken substantially along line 10-10 of FIG. 7 showing that fragment of the cassette which is illustrated in FIG. 9 but including the thread as it is nipped before the cassette is fully seated in the sewing machine,

FIG. 11 is a cross-sectional view similar to FIG. 10 but showing the thread npper released as when the cassette is fully seated in the sewing machine, and

FIG. 12 is a perspective view of the thread cassette of this invention with the cover closed.

Referring to FIGS. 1, 5 and 7, this invention finds utility in a sewing machine indicated generally at 11 having a frame including a bracket arm 12 and a work supporting bed 13. As shown in FIG. 7, the sewing machine includes as one of the stitch-forming instrumentalities a needle 14 secured to a needle bar 15 journaled for endwise reciprocation in a bearing sleeve 16 in the bracket arm 12. The needle bar is imparted endwise reciprocatory movement by a drive link 17 which embraces a crank pin 18 rotated by a sewing machine main shaft 19 in the bracket arm 12. The crank pin 18 also drives a take-up lever 20 which is pivoted as at 21 to an anchor link 22 journaled on a fulcrum pin 23 in the bracket arm. The free extremity of the take-up lever is formed with a thread accommodating take-up eyelet 24 from which eyelet extends a thread introduction slot 25 having its mouth 26 located at a considerable distance from the free extremity of the take-up lever 20.

The take-up constitutes one of a series of thread manipulating elements which are required to operate upon the thread which is directed to the needle in a conventional lockstitch sewing machine. As shown in FIGS. 3 to 6, the sewing machine bracket arm also carries a thread tensioning device, indicated generally at 30, which includes opposed thread engaging disks 31 arranged on a stud 33. The disks 31 may be biased together by any known arrangement and serve frictionally to resist passage of a thread therebetween.

Also effective to manipulate the thread adjacent to the tensioning device is a check spring 34 shiftable angularly about the stud 33 of the tensioning device. Also shiftable supported for turning movement about the stud 33 of the tensioning device is a plate 36 formed with a thread guiding finger 37 for engaging and guiding the thread between the tension disks 31 and the check spring 34. The plate 36 also includes bifurcated tangs 38 by which the plate may be turned to shift the thread guiding finger 37 selectively between effective and retracted positions as will be described hereinbelow.

The thread tensioning device 30, the check spring 34 and the thread take-up eyelet 24 thus represent three different thread manipulating elements to which a needle thread of a lockstitch sewing machine must be directed in sequence in order for lockstitches to be formed properly. In accordance with this invention,

these thread manipulating elements may be threaded simultaneously by the act of insertion into the sewing machine frame of a thread cassette indicated generally at 40.

FIG. 5 illustrates a fragment of the sewing machine bracket arm and indicates the manner in which a cassette accommodating space 41 is defined therein. A sheet metal plate 42 secured to the bracket arm 12 defines the inside wall of the cassette accommodating space and an escutcheon panel 43 exteriorly on the bracket arm defines the outside wall thereof. At each side, the sheet metal plate 42 is formed with out-turned channel elements 44 and 45 which not only define opposite ends of the cassette accommodating space 41 but which provide tracks slidably to accommodate the cassette 40 for translatory movement into the cassette accommodating space 41.

As shown in FIGS. 4 and 5, the tensioning device 30, check spring 34, and thread guiding finger 37 for the check spring are positioned completely within the cassette accommodating space 41, while the take-up lever 20 only partly projects into the cassette accommodating space. The mouth 26 of the thread introduction slot 25 leading to the take-up eyelet 24, as shown in FIG. 7, is arranged completely beyond the cassette accommodating space 41 at the opposite side of the sheet metal plate 42.

Three separate techniques are used to direct the thread to the tensioning device 30 and check spring 34, to the thread guiding finger 37, and to the take-up eyelet 24 respectively. As will be described in greater detail hereinbelow, these three techniques involve: (1) a direct insertion of the thread from the cassette into the thread manipulating element as in the case of the tensioning device and check spring; (2) a shift of the guide or element to be threaded from a retracted position to an operative position in engagement with the thread as in the case of the thread guide 37; and (3) an arrangement for deflecting the thread out of the cassette accommodating space and into cooperative relation with a remotely positioned element as in the case of the thread take-up.

For influencing insertion of a thread to the take-up eyelet, a U-shaped thread deflecting member or fin 50 is provided of which a detached view is shown in FIG. 8. The deflecting member 50 includes a pair of spaced substantially parallel arms 51 and 52 joined by a web 53. The spaced arms 51 and 52 are formed with thread camming surfaces 54 and 55, respectively, which begin closely adjacent to the web at the top and are inclined downwardly away from the web 53. The thread camming surface 54 terminates at the bottom in a large notch 56, while the thread camming surface 55 continues below that of the thread camming surface 54 and terminates in a rearwardly projecting lip 57 beneath which the arm 52 is formed with a notch 58 extending closely adjacent to the web 53. Below the notches 56 and 58, the arms 51 and 52 straddle and are secured to a support block 59 into which is threaded a fastening screw 60 by which the thread deflecting member 50 is secured to the sheet metal plate 42. Preferably, the thread deflecting member 50 is secured to the sheet metal plate 42 with the web 53 and the upper portion of the thread camming surfaces 54 and 55 disposed within the cassette accommodating space 41. The spaced arms 51 and 52 of the thread deflecting member extend opposite a vertical slot 61 in the sheet metal

plate 42 and the lip 57 on the thread camming surface 55 extends through the vertical slot 61 to a position within the sewing machine bracket arm rearwardly beyond the cassette accommodating space 41 as shown clearly in FIG. 7.

The sheet metal plate 42 carries a stop pin 65 and the web 53 of the thread deflecting member 50 on the sheet metal plate 42 also carries a stop pin 66, which stop pins together define the seated position for the cassette 40 in the cassette accommodating space 41.

The sheet metal plate 42 additionally, is formed with an inturned finger 67 to which is secured as by welding a resilient tab 68 formed with an angularly bent free extremity 69 to serve as a thread nipper release as will be described hereinbelow. For a fine adjustment of the position of the resilient tab 68, a stop screw 70 threaded into the support block 59 of the thread deflecting member is provided.

Referring particularly to FIGS. 2, 3, 4 and 12, the 20 construction of the thread cassette 40 will now be described. The cassette includes a casing 71 formed with straight and parallel side edges 72 and 73 which are shaped for cooperation with the channel elements 44 and 45 of the sheet metal plate 42 on the sewing machine bracket arm and serve to guide the cassette in its movements into and out of the cassette accommodating space 41 in the sewing machine. The casing 71 is formed with a cavity 74 for accommodation of a supply of thread such as the thread spool 75. For this purpose a spool pin 76 with thread spool frictioning means such as a spring 77 may be attached to the cassette casing 71. A lid 78 having hinge elements 79 and 80 attached to the cassette casing closes the thread accommodating cavity 74 and may be opened selectively for inspection or refill if the thread supply. An aperture 81 may be provided in the lid so that the remaining supply of thread within the cassette may be readily viewed.

The casing 71 of the cassette is provided with a plurality of thread guides to which thread from the thread spool 75 must be directed in sequence in order to ready the cassette for use with the sewing machine. A first thread guide 85 is secured by a fastening screw 86 in a position in axial spaced relationship to the thread spool 75. A second thread guide 87 secured by a fastening screw 88 at one side of a recess 89 formed in the casing 71 of the cassette. A third thread guide 90 which is arranged at the opposite side of the recess 89 in the casing 71 and a fourth thread guide 91 which is arranged at one side of a second recess 92 in the casing 71 may be formed integrally and fastened by screws 93 to a bracket 94 secured by screws 95 to the casing. The thread guides 85, 87, 90 and 91 may be similarly constructed and provided each with a thread introduction slot 96 so that the thread may be entered laterally therein in a manner referred to as "self-threading" in the sewing machine art.

A fifth thread guide indicated generally at 97 is arranged at the opposite side of the second recess 92 in the cassette casing and is preferably of a different construction than the other thread guides. The fifth thread guide which is illustrated in disassembled perspective in FIG. 9 and is illustrated in cross-section in FIGS. 10 and 11, includes a "U"-shaped body member 98 formed with spaced substantially parallel arms 99 and 100 extending upwardly from a web portion 101 at the bottom. A thread supporting blade 102 is arranged between the arms 99 and 100 of the body member 98 so

that a sinuous path of thread will be defined by arms 99 and 100 and the thread supporting blade 102. The arms 99 and 100 are preferably each formed with a down-turned thread retaining finger 103, which fingers serve to discourage inadvertent escape of a thread once introduced into the sinuous path under the arms 99 and 100 and over the blade 102. Against the outside of the arm 99 of the U-shaped body member 98 is arranged a thread nipping blade 104 formed with a downwardly extending nipper releasing arm 105. A thread nipper leaf spring 106 is positioned alongside the thread nipping blade 104. The leaf spring 106, thread nipping blade 104, the thread supporting blade 102, and the U-shaped body member 98 may all be secured to the thread cassette casing 71 by a fastening screw 107. The thread supporting blade 102 is preferably formed with an elongate aperture 108 for the fastening screw 107 to permit limited adjustment of the vertical position of the blade 102 to provide nicety of control of the thread passing through the fifth thread guide 97.

Projecting vertically beneath the U-shaped body member 98 is a wire thread guide 109 through which the thread is directed as it passes from the cassette.

As shown in FIG. 2, the casing 71 of the cassette lid 78 may be formed with shallow channels 110 to provide for passageways through which the thread may extend between the successive thread guides of the cassette. The lid 78, moreover, is formed with a recess 111 complementary to the recess 89 in the casing.

Adjacent the recess 89, the casing 71 of the thread cassette carries a bracket 120 which includes a finger 121 adapted, as will be described hereinbelow, to cooperate with the bifurcated tangs 38 on the plate 36 carrying the thread guide finger 37 to shift the thread guiding finger from retracted to operative position upon insertion of the cassette into the sewing machine.

The bracket 120 is also formed with a forwardly inclined check spring engaging blade 122 effective as shown in FIG. 6 during insertion of the cassette into the sewing machine to engage and depress the check spring 34. Such depression of the check spring insures a favorable lead of thread between the check spring and the thread tensioning disks 31 so that the thread will find its way beneath the thread guiding finger 37. When the cassette is completely seated in the sewing machine as shown in FIG. 3, the blade 122 will have slipped past the check spring 34 allowing the check spring freedom for operative movement. A beveled upper edge 123 of the blade 122 provides for passage of the blade upwardly past the check spring without interference when the cassette is removed.

The cassette casing 71 has pivoted thereon as at 129 a thread nipping lever 130 which includes a thread contacting finger 131 at one extremity of the lever for contact with the first thread guide 85 to resist movement of thread therethrough. A leaf spring 132 carried in the cassette casing 71 biases the thread contacting finger into effective thread nipping position against a thread guide 85. The thread nipping lever 130 also includes a release arm 133 which is influenced by the channel element 45 of the sheet metal plate 42 during the last motion of insertion of the cassette into the sewing machine to shift the thread nipping lever against the force of the leaf spring 32 and to hold the nipper into open position as shown in FIG. 3.

The thread nipping lever 130 engages the thread at one side of the thread manipulating instrumentalities to

which the thread is to be introduced. The thread nipping blade 104 engages and restricts passage of the thread at the opposite side of the thread manipulating instrumentalities to be threaded. Preferably, the thread nipping blade 104 exerts a greater frictional resistance to movement of the thread than does the nipper lever 130 so that if the influence of both nippers is exceeded, additional thread will be drawn from the thread supply and not from the free end of thread which might unthread one or more of the cassette thread guides. When the cassette is moved into final position within the cassette accommodating space 41 the nipper release arm 105 of the thread nipping blade 104 will contact the free extremity 69 of the tab 68 thus shifting the thread nipping blade 104 into an open position as shown in FIG. 11.

In operation, a cassette 40 when provided with a supply of thread and threaded as shown in FIG. 2 is ready for insertion into the sewing machine after the lid of the cassette is closed. Insertion of the cassette into the thread accommodating space 41 of the sewing machine simultaneously introduces thread to the thread manipulating instrumentalities by the three different techniques described above. For threading the tensioning device 30 and the check spring 34, the span of thread between the second and third thread guides 87 and 90 of the cassette will be introduced directly thereto. The thread guiding finger 37 will be shifted into retracted position shown in FIG. 6 when the cassette had been previously removed from the machine. During the final movement of the cassette into position the finger 121 on the cassette will shift the plate 36 and pull the thread guiding finger toward and into engagement with the thread which extends from the tensioning device to the check spring so that the relationship of parts as shown in FIG. 3 will result.

The thread take-up eyelet 24 will be threaded when the cassette is inserted into the sewing machine by the action of the thread deflecting member 50 which will engage the thread which spans the second recess 92 between the thread guides 90 and 91. The thread camming surface 54 and 55 will shift this span of thread rearwardly through the slot 61 in the plate 42 into the sewing machine bracket arm and as the downward movement of the cassette proceeds, this deflected limb of thread will be carried over the lip 57 of the thread camming surface 55. As shown in FIG. 7, the take-up lever 20 at the bottom of its stroke will be positioned such that the thread introduction slot 25 and particularly the mouth 26 of the slot will be arranged directly beneath the lip 57 of the thread deflecting member. When the cassette is shifted completely into the cassette accommodating space in the sewing machine, therefore, the thread will be introduced to the slot 25 and thence to the eyelet 24 of the take-up lever. It is a requirement for successful operation of the easy threading arrangement of this invention that the main shaft 19 of the machine be turned prior to insertion and withdrawal of the cassette into a predetermined position in which the take-up lever 20 will occupy substantially the lowest position of its path of motion as shown in FIG. 7. A set of cooperating indicia 140, 141 on the sewing machine bracket arm 12 and on a handwheel 142 on the main shaft 19 serves as reference for the setting of this predetermined machine position for insertion and removal of the cassette.

Since the two spans of thread in the cassette extending one between thread guides 87 and 90 and the other between thread guides 91 and 95 will be held taut by the operation of thread nippers 104 and 131 while the cassette is in any position other than a position completely seated in the cassette accommodating space 41 in the sewing machine, these two spans of thread will be directed to the thread manipulating instrumentalities upon insertion of the cassette into the sewing machine, and these spans of thread will be withdrawn from the instrumentalities when the cassette is lifted out of the sewing machine frame. A recess 150 may be formed in the top surface of the sewing machine bracket arm 12 providing a better grip for the operator in depressing and removing the cassette from the sewing machine.

When the cassette has been inserted into the sewing machine and the thread manipulating instrumentalities simultaneously threaded thereby, the wire guide 109, and consequently, the free end of the thread which extends through the wire thread guide, will protrude beneath the level of the escutcheon plate 43 as shown in FIG. 7, so that the operator may easily grasp this thread and draw it downwardly to thread the needle 14 thus completing preparation for sewing.

The cassette threading arrangement of this invention is particularly advantageous where numerous changes of thread are necessitated in the operation of the sewing machine, as where color changes may be required frequently, or the like. With a number of cassettes 40 available each provided with a different type or color of thread, the machine may be readied for sewing with a different color or type of needle thread simply by removing one cassette, replacing another in its place, and rethreading the needle with the fresh thread. With another cassette in place in the sewing machine the path of the thread from the thread spool in the cassette to the needle becomes a free path when the thread nippers 131 and 104 are released. Any use of the thread which is possible with conventional thread arrangements for sewing machine may thus be availed of with the present cassette, for instance, bobbin replenishment while the bobbin remains in place in the loop taken is compatible with the present cassette arrangement and any known type of sewing operation such as darning, embroidery, or the like is equally compatible therewith.

With a number of cassettes available each provided with a different color or type of thread, storage of thread is no longer fraught with the problem of thread snarling since the nippers 102, 131 will be effective to prevent accidental unwinding of the thread spools while the cassettes are stored.

Having set forth the nature of this invention, what is claimed herein is:

1. A thread cassette for supplying thread to a sewing machine having at least one thread manipulating element, said thread cassette comprising a casing formed with guide means dictating insertion of said thread cassette into a sewing machine only in predetermined orientation of said thread cassette, support means on said casing for a supply of thread, thread guides on said casing adapted to accommodate in seriatim a thread leading from a supply of thread on said support means, and including successive thread guides arranged to position therebetween a span of thread for introduction to the sewing machine thread manipulating element when the

thread cassette is inserted into the sewing machine in the predetermined orientation dictated by said guide means, and releasable thread nipping means effective on a thread on each side of said successive thread guides during insertion of said thread cassette into a sewing machine.

2. A thread cassette comprising a casing, support means on said casing for a supply of thread, a series of thread guides on said casing adapted to accommodate in seriatim the thread leading from a supply of thread on said support means and defining at least one span of said thread between successive ones of said thread guides, releasable thread nipping means effective on said thread at each side of said at least one span of said thread, and orientation means on said casing effective to constrain said thread cassette to move in a direction substantially perpendicular to said at least one span of said thread.

3. An easy threading arrangement for a sewing machine having a frame, a thread carrying stitch-forming instrumentality, and at least one thread manipulating element associated with said stitch-forming instrumentality in said frame, said sewing machine frame being formed with a reception track means defining a space for accommodation of a thread supply cassette, means on said sewing machine casing and projecting into said cassette accommodating space for directing a span of thread to said thread manipulating element, a thread supply cassette including a casing, support means for a thread supply in said casing, a series of thread guides in said casing for accommodating in seriatim a thread from thread supply on said support means and including a pair of successive thread guides arranged to define therebetween a span of thread for delivery to said thread directing means upon insertion of said cassette along said reception track means.

4. An easy threading arrangement for a sewing machine as set forth in claim 3 in which a thread nipping means is provided on said thread supply cassette effective to clamp a thread passing through said thread guides relatively to said cassette casing on opposite sides of said pair of successive thread guides defining said span of thread, and interengaging releasing means for said thread nipping means carried on said sewing machine frame and on said cassette casing effective when said cassette is positioned completely within said accommodation space on said sewing machine frame.

5. An easy threading arrangement for a sewing machine as set forth in claim 4 in which said thread nipping means includes separate thread nippers effective on a thread on opposite sides of said pair of successive thread guides, and in which that one of said thread nippers which is effective on the thread between said thread supply and said pair of thread guides is materially less effective than the other one of said thread nippers.

6. An easy threading arrangement for a sewing machine as set forth in claim 3 in which associated with said stitch-forming instrumentality are a plurality of thread manipulating elements including a movable thread take-up member and a thread tensioning device, and in which said thread supply cassette includes in said series of thread guides a pair of successive thread guides corresponding to each of said plurality of thread manipulating elements, each pair of thread guides arranged to define therebetween a span of thread for delivery to thread directing means associated with a re-

spective one of said plurality of thread manipulating elements.

7. An easy threading arrangement for a sewing machine as set forth in claim 6 in which a check spring is arranged between said thread tensioning device and said thread take-up element on said sewing machine frame, a shiftable thread guide is carried on said sewing machine frame for movement from a retracted position out of the path of a thread from the thread tensioning device to said check spring to an effective position in 10 the path of a thread from the thread tensioning device to the check spring, and in which an operating member for said shiftable thread guide is carried by said thread supply cassette and is operative to shift said thread guide into effective position when the thread supply 15 cassette is positioned completely within said accommodation space on said sewing machine frame and is operative to shift said thread guide into retracted position when said thread supply cassette is removed from said accommodation space.

10
15

8. An easy threading arrangement for a sewing machine as set forth in claim 3 in which said thread manipulating element comprises a thread take-up arm formed with a thread eyelet and including a thread introducing slot leading from the thread eyelet to an opening exteriorly on the thread take-up arm, and in which said means for directing a span of thread to said thread manipulating element comprises a thread deflecting fin carried on said sewing machine frame and having one extremity projecting into said thread cassette accommodation space to deflect a span of thread defined on said cassette along a camming surface formed on said thread deflecting fin, said camming surface on said thread deflecting fin extending into juxtaposition with the exterior opening of the thread introducing slot in said thread take-up arm in one predetermined position of said sewing machine stitch-forming instrumentalities.
